DIE CASTING MACHINE

Raymond J. Schultz, Madison, Wis., assignor to
 Madison-Kipp Corporation, Madison, Wis., a
 corporation of Wisconsin

Application December 7, 1936, Serial No. 114,716

15 Claims. (Cl. 22—92)

This invention relates to die casting machines and particularly to the mechanism in such machines for opening and closing the multi-part die incident to the charging of the die and the 5 ejection of the casting.

It is necessary in die casting machines employing multi-part separable dies to have certain mechanism for bringing the parts together to receive a charge of metal, and then for opening the die by separating the die parts to permit 10 removal of the casting. Generally, removal of the casting is effected automatically during, and as a result of operation of automatic ejecting means caused by the opening movement of the 15 die.

In present practice, it is usual to run the die casting apparatus at high speed in order to meet the demand for quantity production of castings. As a result, the closing movement of the die 20 takes place at a comparatively high rate of speed with a resultant objectionable slamming or banging of the die parts as they engage to close the die. Similarly, due to the high speed of operation of the machine, the die opening movement is effected very rapidly and, consequently, there 25 is an undesirable slamming or banging as the automatic ejecting means are operated at the end of the die opening movement.

It is a purpose of the present invention to 30 provide improved die operating mechanism which will actuate the die during its closing movement so as to eliminate this objectionable slamming at the end of the closing operation and yet close and hold the die parts in a manner to cause them to fit accurately and tightly together.

A further purpose is the provision of a die operating mechanism which, in operating the movable die part (or parts) to open the die, will actuate the movable die part so as to eliminate 40 the undesirable slamming or banging of the parts incidental to operation of the automatic ejecting means and still move the die part in a manner to effect proper operation of the ejecting mechanism.

A further object is the designing of die operating means which, in opening the die after a casting has been shot, will cause the movable die part (or parts) to begin the opening movement suddenly and at a comparatively high speed. 45 This results in proper "breaking" of the die, so that if any cores are used they are pulled from the casting much more easily and cleanly, and the resulting jerk serves effectively to break the casting loose from the stationary part of the die when this arrangement is used.

Another object is the provision of means for effecting adjustment of the die actuating mechanism in order to compensate for use of different sized dies. Other objects and advantages will appear from the following detailed description and the accompanying drawings showing a practical embodiment of the invention, wherein:

Figure 1 is a fragmentary front elevation of a die casting machine to which the invention has been applied, certain of the parts being broken away and the die being shown in closed position.

Fig. 2 is an elevation of the right hand end of the machine as it appears in Fig. 1, certain of the parts also being broken away.

Fig. 3 is a fragmentary view similar to Fig. 1 showing the die fully opened and the ejecting means operated.

Figs. 4 to 7 are similar elevational views, partly in section, of the exhaust-control valve operating means for the cylinder forming part of the 20 pressure-fluid type die actuating mechanism used, the parts being shown in the successive positions assumed by them as the die moves from closed to full open position.

Fig. 8 is a plan of the valve operating mechanism as shown in Fig. 4.

Fig. 9 is a section on line 9—9 of Fig. 1 showing the hand control valve for the die actuating mechanism in the position to which it is moved to close the die.

Fig. 10 is a section on line 10—10 of Fig. 9, except that the parts are shown diagrammatically in order to bring the several passages and ports into one plane; and

Fig. 11 is a similar view of the valve moved to 35 the die opening position.

Referring particularly to Figs. 1 to 3, the machine shown comprises a frame made up of a base 12 having legs 13 and supporting a hollow frame body 14. Body 14 is open at the bottom 40 and base 12 at the top to provide free space for the die operating piston and cylinder unit described later. Machine screws 15 secure base 12 and body 14 together at their abutting edges.

Frame body 14 has an upright portion 16 to 45 which the fixed half 17 of the die is removably secured in any suitable manner. The movable half 18 of the die is detachably affixed to one end of a ram 19 mounted for reciprocation in an opening 20 extending through a second upright portion 21 at the opposite end of the machine. An elongated pinion 22 is mounted in upright 21 and meshes with rack teeth 23 on ram 19, so that rotation of the pinion in a clockwise direction (Figs. 1 and 2) serves to open the die 55

while rotation in the opposite direction serves to close it. Hand wheel 24 comprises manual means for directly operating pinion 22.

Toggle means are interposed between the opposite end of ram 19 and extensions 25, 25' of the frame 14 to lock the die in closed position, as appears in Fig. 1. The toggle means comprise link 26 pivotally connected at 27 to the ram and also pivotally connected at 28 to links 29, 29'. 10 The latter are pivotally connected at 30, 30' to the frame, these pivotal connections being horizontally adjustable by set screw means 31, 31' so that the toggle locking mechanism may be set to function properly when used with dies of 15 slightly varying thicknesses.

An upright link 32 is pivotally connected at 28 to the toggle means for operating the same. The lower end of this link is pivotally connected at 33 with a lever 34 pivotally mounted at 35 on 20 a rod 36 extending between the legs of the frame. The outer end of lever 34 is in the form of a treadle 34'. Suitably secured to the floor near the end of the machine is a bracket member 37 having standards 38, 38' carrying a pin 39 on 25 which is pivoted a lever 40. The outer end of lever 40 forms a treadle 41, while the inner end 40' of the lever is disposed beneath treadle 34'. A spring 42 urges lever 40 towards the position of Fig. 1.

30 With the parts in the die-closed position of Fig. 1, when the operator steps on treadle 41, the inner end 48' of lever 40 raises the treadle end of lever 34 and thus causes link 32 to break upwardly the toggle formed by links 26, 29 and 35 29', so that hand wheel 24 may be turned to quickly open the die, as shown in Fig. 3. Spring 42 returns lever 40 to its normal position when treadle 41 is released. To close the die and lock it, hand wheel 24 is rotated in the opposite direction, and as movable die part 18 approaches closed position, the operator steps on treadle 34'. This causes link 32 to straighten out the toggle and thus tightly lock die parts 17 and 18 together. Hand wheel 24 and treadles 34' and 41 45 are for manual manipulation of the machine, particularly when setting the die for a new operation.

Since the means for supplying the metal charge to the closed die form no part of the present 50 invention, the charging means used are merely shown in dotted lines in Fig. 2, in position for shooting a casting. Obviously any other suitable type of means for charging the die with metal in molten, or other moldable condition, may be 55 used.

In general, the metal charging mechanism illustrated comprises a unit 43 pivotally supported at 44 on the machine frame for automatic vertical swinging movement between the elevated 60 die charging position illustrated when the die is closed, and a lowered, inoperative position when the die is open. Charging unit 43 includes a furnace 45, a melting pot 46 and a gooseneck 47. The latter receives the molten metal from pot 46 65 and is adapted to discharge it under pressure through gooseneck nozzle 48 into the closed, side-gated die at the parting line. Manually controlled pressure fluid means in the form of a piston and cylinder unit 49 and a connected piston 50 ton 58 located in gooseneck 47 serve to feed the metal to the die and apply the necessary pressure thereto.

Charging unit 43 is moved between its die charging and non-operating positions by an operating connection extending between the bot-

tom of the unit and the inner part of foot lever 34. This connection comprises a toggle 51 (Fig. 2) extending between the bottom of unit 43 and one end of a shaft 52 rotatably supported in lugs 53 (only one of which is shown) on the frame. The opposite end of the shaft has a crank 54 to which a link 55 is joined by a universal connection 56, while the lower end of the link also has a universal connection 57 with lever 34.

Thus, when the inner end of foot lever 34 rises during closing of the die, toggle 51 is extended by the mechanism described to swing charging unit 43 upwardly and bring nozzle 48 into charging engagement with the die. Final movement of the nozzle into actual engagement with the die takes place just after the die parts contact. This is effected by a short additional upward movement which lever 34 has after the die parts engage, such movement being permitted by a lost-motion connection between ram 19 and die part 18 described later. Similarly, when the inner end of lever 34 descends in opening the die, the first part of this movement swings unit 43 downwardly to disengage the nozzle from the die, whereupon the die opens while the unit continues to descend.

Slidably mounted for limited movement on the outer end of ram 19, which has a pocket 19' therein, is a carriage 58 to which movable die half 18 is detachably affixed by screw means 30 18'. Carriage 58 has a hollow, open-ended extension 59' which receives the ram. This extension carries screw lugs 60 projecting into corresponding, elongated slots 61 in the ram to limit the outward movement of the carriage on the 35 ram. A coil spring 62 is placed under compression in pocket 19'. Thus, when the die is open, as appears in Fig. 3, spring 62 extends the die carriage and ram assembly so that each lug 60 40 engages the outer end of its slot 61.

However, during the latter part of the movement of ram 19 to close the die, die part 18 engages fixed die part 17 to close the die, and then the slight overtravel of foot lever 34 referred to before, and the resulting additional movement of ram 19, first cause further compression of spring 62 to yieldably hold the die parts together and then rigidly lock them together as the outer end of the ram engages the inner end 63 of die carriage extension 59' (Fig. 1). During 50 this compression of spring 62, lugs 60 move to the other ends of their slots and metal charging nozzle 48 is moved into engagement with the closed die. As retraction of the ram starts in opening the die, spring 62 expands and lugs 60 55 slide outward in their slots to permit disengagement of metal nozzle 48 from the die before it opens. Lugs 60 then engage their outer slot ends so that the die is pulled open and the parts referred to resume their positions of Fig. 3. It 60 will be noted that the lost-motion, resilient connection between the ram and the die carriage permits the use of die parts of different thicknesses.

The casting ejecting means, as shown in the die 65 open position of Fig. 3, include a reciprocable ejecting plate 65 located in chamber 66 of die carriage 58. Ejection return pins 67 and ejector pins 68 project slidably through passages in die half 18 and are attached to plate 65. The means 70 for automatically operating the ejecting means comprise ejector bars 69 slidably mounted in passages in die carriage 58. The inner ends of these bars project into chamber 66 to operate plate 65, while the outer ends carry adjustable screws 69' 75

whereby the length of the bars may be adjusted.

With this arrangement, as shown in Fig. 1, when the die closes return pins 67 are pushed in by the fixed die half to move plate 65 to the right and draw in ejector pins 68. This movement of plate 65 pushes out ejector bars 69, ready for operation to eject the casting when the die opens. As the die opens, the ejecting means remain in the position mentioned until screws 69' of ejector bars 69 strike upright 21 of the frame near the end of the opening movement. This causes bars 69 to be forced through the die carriage to operate plate 65 and pins 68 to eject the casting. As the opening movement of ram 19 is completed, the parts of the ejecting mechanism return to their positions of Fig. 3, with plate 65 against die part 18.

The power means for actuating the described mechanism for opening and closing the die, and to which my invention more particularly relates, will now be described. Located within the hollow machine frame is a pressure fluid unit comprising a cylinder 70 and a double-acting piston 71. Cylinder 70 has a perforated lug 70' whereby it is pivotally mounted at its upper end on a rod 72 supported in the machine frame. Piston rod 73 is pivotally connected at its lower end 73' to the inner end of foot lever 34. When the die is closed, as in Fig. 1, the piston is in the upper end of the cylinder, and with the die open, as shown in Fig. 3, the piston is located in the bottom of the cylinder.

Compressed air, or other suitable fluid is fed to and exhausted from opposite ends of cylinder 70 by pipe line 74 leading to the bottom thereof and pipe line 75 leading to the top. A bracket 76 secured to extensions 25, 25' of the machine frame carries valve means for manually and primarily controlling the flow of pressure fluid through pipe lines 74 and 75. These valve means comprise a casing 77 having a ported valve seat cover 78 secured thereto (see Figs. 9, 10 and 11 for details). Chamber 79 in the casing contains a rotatable ported valve member 80 urged into tight contact with seat member 78 by coil spring 81. A pipe 82 leading from a suitable source of supply continuously furnishes pressure fluid at full pressure to valve chamber 79. Cylinder pipe line 74 connects to passage 83 in cover 78, pipe line 75 to passage 84, and an exhaust pipe 85 to passage 86, all of these passages opening onto the lower face of the cover in arcuate arrangement (see Fig. 9). Also arranged in aligned, arcuate arrangement are a through passage 87, a similar passage 88, and a groove 89 in valve disk 80. Valve 80 is operated by a stem 90 (Fig. 9) having a handle 91 secured to its upper end (Figs. 1 and 2).

With the die closed and piston 71 elevated as in Fig. 1 valve handle 91 is located in the rear-most position of Fig. 1, which is the dotted line or "Die close" position of Fig. 9. At this time, the valve passages are connected as indicated in Figs. 9 and 10, full pressure flowing from valve chamber 79 through passage 87 to pipe 74 and thence to the lower end of cylinder 70. At this time passage 88 is blanked, but groove 89 connects passages 84 and 86 so as to exhaust the upper end of cylinder 70 through pipe 75 to exhaust pipe 85. When the die is to be opened, handle 91 is moved to its foremost position, i. e., the "Die open" position of Fig. 9. The position of the ports at this time are shown in Fig. 11, in which full pressure from valve chamber 79 flows through passage 88 to pipe 75 and thence to the

top of cylinder 70 to force piston 71 down to open the die. At the same time, passage 87 is blanked, but groove 89 connects passages 83 and 86 to vent the bottom of cylinder 70 through pipe 74 to exhaust pipe 85. Movement of handle 91 to the "Neutral" position of Fig. 9, blanks passages 87 and 88, but connects passages 83 and 84 to passage 86 and thus vents both ends of cylinder 70 to exhaust pipe 85.

The rate of escape from exhaust pipe 85 to the atmosphere of compressed air vented thereto from the ends of cylinder 70 is regulated automatically by the die operating mechanism in the particular manner described below, so as to vary the power applied to the die operating mechanism by piston 71 during the die opening and closing movements thereof and thus, as explained later, control the speed of movement of the operating mechanism in a manner to eliminate the objectionable slamming of the parts at the end of each stroke of ram 19. Exhaust pipe 85 leads to an inlet port 92 in a valve casing 93 (Figs. 4 to 8) secured by screws 94, 94 to the rear face of the machine frame. Threaded into the open end of cylindrical chamber 95 of the valve casing is a gland 96 having an adjusting head 97. An exhaust port 98 is provided in the valve casing.

Mounted for reciprocation in valve chamber 95 is an exhaust-control valve 99 having a tapered surface 99' adapted to coact with a tapered valve seat 92' to regulate the flow of exhaust fluid from pipe 85 into chamber 95, whence it passes through annular space 100 between the valve and the casing and out through exhaust opening 98. Since the area of annular space 100 is greater than the area of either inlet port 92 or exhaust port 98, which latter are the same, it will be clear that the rate at which pressure fluid escapes from exhaust port 98 will be directly controlled by the area of the annular space 101 between tapered valve seat 92' and tapered valve surface 99'. This area of course varies according to the distance between the valve and its seat.

As valve 99 begins to open, the escape of exhaust fluid from port 92, and hence from port 98, is restricted, but quickly increases until the area of annular space 101 equals that of exhaust port 98 or inlet port 92. This causes unrestricted or maximum rate of flow of exhaust fluid from port 98 which continues until the valve reaches its extreme open or right hand position (Figs. 4 and 7). As valve 99 closes, the reverse of the action described takes place, maximum or unrestricted venting taking place at ports 92 and 98 until the valve reaches the point where the areas of space 101 and exhaust port 98 are equal, and then restriction of the exhaust flow being quickly brought about as the valve moves closer to its seat.

Valve 99 is operated by its stem 102, which extends through gland 96, and a coil spring 103 in the valve casing which continuously urges the valve towards its seat to restrict the escape of exhaust fluid. The load imposed on valve 99 by its spring may be changed by screwing gland 96 in or out to vary the resistance of the valve to the escape of exhaust fluid and thus regulate the rate of its escape. Valve stem 102 is pivotally connected at its outer end by a fixed stud 102' to the forked end 105 of a link 106. A nut 104 secured on stud 102' by a cotter pin acts on a spring washer 104' to set up sufficient frictional resistance to prevent pivotal movement of link 106 unless it is positively moved, as explained later. The outer end of link 106 has 75

- a U-shaped slot 107 therein. Projecting into the end of the upper arm 108 of slot 107 is a screw 109 which is adjustably mounted in the link and secured by a lock nut 109'. By releasing 5 the lock nut and adjusting the screw or stop inwardly or outwardly, the effective length of the slot arm 108 may be varied. A similar adjusting screw or stop 110 and lock nut 110' are provided in the lower arm 111 of the slot.
- 10 Ram pinion 22 projects from the rear face of the machine and has an annular groove 112 which receives the lower curved edge of a retainer plate 113 secured to the frame by screws 114. Rigidly secured on the end of pinion 22 by a screw 115 is a radially disposed arm 116. This arm is also keyed to the pinion by a pin 117 to prevent movement of the arm about screw 115. The outer end of arm 116 carries a headed stud 118 which extends through and is adapted 15 to operate in U-shaped slot 107 of link 106 as pinion 22 oscillates back and forth during operation of the machine.
- Fig. 4 shows the position of arm 116 and stud 118 when the die is in the closed position of Fig. 1. Fig. 7 shows the position of the arm and stud 118 after the die has been fully opened as shown in Fig. 3. During this operation pinion 22 revolves and stud 118 travels in an arcuate path somewhat less than 360° in a counterclockwise 20 direction, as shown in Figs. 4 to 7. As the die is closed, pinion 22 revolves in the opposite direction and stud 118 retraces its arcuate path of movement to return the parts to the position of Fig. 4. With the arrangement and proportioning of the parts shown, valve stem 102 aligns 25 with the center of pinion 22, and the arcuate movement of stud 118 is the same both above and below a horizontal plane extending through the axis of pinion 22.
- 30 Stud 118 is adapted near each end of its arcuate movement to engage either stop 109 or 110 and thus pull valve 99 away from its seat, to permit unrestricted exhaust, by shifting link 106 to the right as the stud completes the last portion 35 of its arcuate movement. Shortly after the beginning of its return movement in either direction, stud 118 moves out of engagement with stop 109 (or 110) and spring 103 is free to again move the exhaust-control valve towards its seat to restrict the exhaust. Therefore, during the intermediate and greater portion of the arcuate 40 movement of stud 118 in either direction, and the corresponding movement of ram 19, valve 45 99 is controlled by spring 103 to restrict the escape of exhaust fluid from the non-working end of power cylinder 70 and thus retard movement of piston 71. Stud 118 at this time 50 imposes no movement to valve 99, but merely travels through U-shaped slot 107, this being permitted 55 by the necessary pivotal movement of link 106 on pin 102'. The tension provided by spring washer 104' prevents link 106 from dropping of its own accord during movement of stud 118 from the position of Fig. 4 to that of Fig. 7, 60 and thereby causing operation of the stud only in the upper half of U-shaped slot 107.
- The point near each end of the arcuate movement of stud 118, and consequently the corresponding point near each end of the reciprocal 65 movement of ram 19, at which the stud engages stop 109 or 110 to move valve 99 to its unrestricted exhaust position, may be varied by adjustment of stops 109 and 110. In their illustrated positions, these stops project the same 70 distance into the ends of the U-shaped slot so

that, with the parts of the machine proportioned and arranged as shown, valve 99 will be operated to permit unrestricted exhaust at the same distance from each end of the stroke of ram 19 and from each end of the stroke of piston 71. As 5 shown in the drawings the adjustment of stops 109 and 110 is such that unrestricted exhaust past valve 99 will take place shortly before the die parts contact in closing and shortly before the ejecting means are operated in opening the 10 die.

Starting with the die closed, as shown in Fig. 1, the general operation of the machine is as follows:—

At this time valve handle 91 is in the "Die 15 close" position of Fig. 9 so that air under pressure in the bottom of cylinder 70 holds the die closed, while stud 118 holds exhaust control valve 99 in the position of Fig. 4 to permit free exhaust from the top of cylinder 70. The ejecting means are retracted and ram spring 62 is compressed, while piston 50 has been elevated following the shooting of a casting.

Upon movement of valve handle 91 to its forward position ("Die open" position, Fig. 9), air 25 under full pressure enters at the top of cylinder 70 to move piston 71 downwardly and start the opening movement of ram 19. The first part of this movement permits spring 62 to expand and nozzle 48 disengages from the closed die. 30 Lugs 60 then engage the ends of their slots and the die parts are separated. During this movement of the ram, stud 118 moves toward the position of Fig. 5, so that valve 99 is forced towards its seat by its spring, but not to the point where 35 restriction of the exhaust flow occurs. As the ram continues to move, and shortly after the die opens, valve 99 quickly moves to its exhaust restricting position as shown in Fig. 5. As this time stud 118 is moving out of contact with stop 40 109 and valve 99 is under full control of spring 103 and the escaping exhaust fluid, which serves to maintain the valve in the restricted flow position of Fig. 5, i. e., with the valve slightly off its seat.

45 Thus it will be noted that, since the exhaust flow from cylinder 70 is not retarded until after the die opens, the full pressure of the compressed air acting on the top of piston 71 is effective to open the die. As a result, movable die part 18 begins its opening movement suddenly and at a comparatively high speed to effectively "break" the die.

As soon as valve 99 moves to restricting position (Fig. 5) and thereby retards movement of 55 piston 71, all of the parts including ram 19 and die part 18 move at a reduced, substantially uniform speed. This continues until just before ejection takes place. Shortly before ejector bar screws 69' engage upright 21, stud 118 engages 60 stop 110 as shown in Fig. 6. Further movement of the stud quickly moves valve 99 to non-restricting or free exhaust position, so as to cause full application to ram 19 of the power acting on piston 71, just prior to operation of the ejecting 65 means. As the ejecting means are operated (Fig. 3), stud 118 moves valve 99 to the final position of Fig. 7. Thus, ejection is accomplished while full fluid pressure is acting on the die opening mechanism. This increases the 70 speed of the mechanism and die part 18 and thus insures complete and efficient ejection of the casting.

Because of the retarded speed at which die 75 part 18 and its operating mechanism travel dur-

ing the major part of the die opening movement, the increased speed of the parts at the end of the opening movement is insufficient to cause any objectionable slamming of the parts as the ejecting mechanism is operated. If the speed of piston 71 were not controlled or its operation cushioned as described, but full exhaust from cylinder 70 permitted during the entire opening movement of the die, the operating parts would gain such momentum during this movement that an extremely objectionable slamming of the parts would take place when the ejecting means are actuated.

The reverse of the above described operation takes place when the die is closed as the result of movement of valve handle 91 to the "Die close" position of Fig. 9. This causes entry of air under full pressure into the bottom of cylinder 70, which latter had been completely exhausted to the atmosphere by valve 99 at the end 10 of the die opening movement. At this time, valve 99 is in the non-restricting position of Fig. 7, which effects free exhausting of the fluid in the upper end of cylinder 70. At the start of the 15 ram return movement, the ejecting means move out of engagement with upright 21 and stud 118 moves clockwise toward the position of Fig. 6 to permit valve 99 to be moved towards its seat by its spring, but not to its restricting position. 20 Upon continued movement of the ram, spring 103 returns the valve to its restricting position of Fig. 6 and stud 118 moves out of engagement with stop 110. Thus the closing movement of the parts begins rapidly, since the parts are 25 subjected to the full force of the pressure fluid entering cylinder 70.

With valve 99 in restricting position, all of the parts continue their closing movement at a retarded, substantially uniform speed until just 30 prior to engagement of the die halves. Shortly before this takes place stud 118 engages stop 109 as shown in Fig. 5. Further movement of the stud quickly moves valve 99 to free exhaust position to thereby cause full application to the ram 35 of the fluid pressure acting on piston 71 just before engagement of the die parts. As the die parts contact and ram 19 overtravels to its final position of Fig. 1, stud 118 moves valve 99 to its original position of Fig. 4, during which time 40 spring 62 is compressed and metal nozzle 48 engages the closed die ready to repeat the casting operation. Closing of the die being thus effected by full application of fluid pressure to the operating mechanism, beginning shortly before the 45 die parts engage, movable die part 18 is brought against the fixed part at a comparatively high speed. As a result the die parts fit accurately and tightly together.

Similarly to the action during the die opening operation, the retarded speed at which the die part 18 and the operating mechanism move during the major part of the die closing movement prevents such increased rate of movement of the parts at the end of the closing movement as 50 would cause objectionable slamming of the parts as they engage.

As explained, the load on valve 99 and thus the rate of movement of piston 71 and ram 19 during the intermediate portion of each stroke, 55 may be varied by adjusting gland 96. This gland may be turned outwardly to increase the speed of the ram or turned inwardly to decrease its speed, in order to obtain the desired rate of movement of the parts in both directions without slamming.

Although a practical embodiment of the in-

vention has been illustrated and described, obviously various modifications thereof are possible without departing from the scope of the invention except as the same may be limited by the appended claims.

What is claimed is:

1. The combination in a die casting machine of a multi-part separable die, one of said parts being adapted for movement to open and close the die; power actuated means, including a double-acting, pressure-fluid piston and cylinder unit, for imparting said movement to the movable die part; means for feeding pressure fluid from a source of supply to the working end of said cylinder throughout the closing movement of the movable die part; and automatic means, actuated as a result of operation of said movable die part, for controlling the flow of exhaust fluid from the opposite end of the cylinder so as to retard said flow during the major portion of the die closing movement, but cause full flow thereof during the last portion of said movement, whereby to regulate operation of the movable die part and thus prevent slamming of the die in closing.

2. The combination in a die casting machine of a multipart, separable die, one of said parts being adapted for movement to close the die to form a casting and open the die to remove the casting; means on said movable die part adapted to be actuated by engagement with a part of the machine during opening of the die to eject the casting; power actuated means, including a pressure-fluid piston and cylinder unit, for imparting said opening movement to the movable die part; means for feeding pressure fluid from a source of supply to the working end of said cylinder throughout the opening movement of said die part; and automatic means, actuated as a result of operation of said movable die part, for controlling the flow of exhaust fluid from the opposite end of the cylinder so as to retard said flow during the major portion of the die opening movement, but cause full flow thereof during the last portion of said movement and beginning prior to actuation of the ejecting means, whereby to regulate operation of the movable die part and prevent slamming of the parts in operating the ejecting means.

3. The combination in a die casting machine of a multi-part separable die, one of said parts being adapted for movement to open and close the die; power actuated means, including a pressure fluid piston and cylinder unit, for imparting said opening movement to the movable die part; means for feeding pressure fluid from a source of supply to the working end of said cylinder throughout the opening movement of said die part; and automatic means, actuated as a result of operation of said movable die part, for controlling the flow of exhaust fluid from the opposite end of the cylinder so as to retard said flow during the major portion of the die opening movement, but cause full flow thereof during the first portion of said movement, whereby to regulate operation of the movable die part so as to insure proper separation of the die parts.

4. The combination in a die casting machine of a multi-part, separable die, one of said parts being adapted for movement to close the die to form a casting and open the die to remove the casting; means on said movable die part adapted to be actuated by engagement with a part of the machine during opening of the die to eject the casting; power actuating means, including a pressure fluid piston and cylinder unit, for im-

- parting said opening movement to the movable die part; means for feeding pressure fluid from a source of supply to the working end of said cylinder throughout the opening movement of said die part; and automatic means, actuated as a result of operation of said movable die part, for controlling the flow of exhaust fluid from the opposite end of the cylinder so as to retard said flow during the intermediate portion of the die opening movement, but cause full flow thereof during the first portion of said movement and during the last portion of said movement beginning prior to actuation of the ejecting means, whereby to regulate operation of the movable die part to thereby insure proper separation of the die parts and prevent slamming of the parts in operating the ejecting means.
5. The combination in a die casting machine of a pair of separable coacting die parts adapted for movement relatively to each other; power actuated means, including a pressure cylinder and piston unit, for imparting said movement to one of said die parts; means for feeding pressure fluid from a source of supply to the working end 10 of said cylinder to operate the movable die part; a spring-loaded valve for resisting the escape of exhaust from the opposite end of the cylinder; and a link connected to said exhaust valve and having a pin-and-slot connection with the power actuated means, whereby engagement of the pin with an end of said slot is adapted to impart opening movement to the exhaust valve during a portion of the movement of the movable die part and thus regulate operation of said die part.

6. In a die casting machine, the combination of a pair of separable, cooperating die parts adapted for relative movement towards each other; power actuating means, including a cylinder and piston unit, for imparting said movement to one of said parts; and means for supplying fluid under pressure to said cylinder and automatically controlling the fluid pressure therein, as a result of operation of said movable part, so that the effective pressure acting on the piston to operate the movable part is relatively low until said part reaches a point a predetermined distance from said cooperating part and then is increased until said parts engage with each other, whereby to regulate operation of said movable part so as to prevent slamming of said cooperating parts.

7. In a die casting machine, the combination of a pair of separable, coacting parts adapted for relative movement towards each other; fluid pressure actuated means for imparting said movement to one of said parts; and means for supplying fluid under pressure to said actuating means and automatically controlling the fluid pressure therein, as a result of operation of said movable part, so that the effective pressure acting to operate the movable part is relatively low until said part is relatively close to said coacting part and then is increased until said parts contact with each other, whereby to regulate operation of said movable part so as to prevent slamming of said cooperating parts.
8. The combination in a die casting machine of a multi-part die, one of said parts being adapted for movement to close the die; means for imparting said movement to the movable die part; and controlling means for causing said die part to move at a substantially uniform, retarded speed until said die part reaches a point a pre-determined distance from the end of said clos-

ing movement and then move at high speed until the die closes.

9. The combination in a die casting machine of a multi-part die, one of said parts being adapted for movement to open the die; ejecting means on said movable die part adapted to be actuated by engagement with a part of the machine during opening of the die; means for imparting said movement to the movable die part; and controlling means for causing said die part to move at retarded speed until said die part reaches a point a predetermined distance from the end of said opening movement and then at high speed during the balance of the opening movement and beginning prior to actuation of the ejecting means.

10. The combination in a die casting machine of a pair of cooperating parts adapted for movement relatively to each other to move said parts into and out of contact; power actuated means, including a cylinder and piston unit, for imparting said movement to one of said parts; means for feeding fluid under pressure from a source of supply to the working end of said cylinder throughout the movement of said part; and automatic means, actuated as a result of operation of said movable part, for controlling the escape of exhaust fluid from the opposite end of the cylinder so as to cause free flow thereof when said movable part is operating relatively closely to said cooperating part, but retard said flow when the movable part operates farther from said cooperating part, whereby to regulate operation of said movable part.

11. The combination in a die casting machine of a pair of separable, cooperating parts adapted for relative movement towards each other; power actuated means, including a pressure fluid cylinder and piston unit, for imparting said movement to one of said parts; means for feeding pressure fluid from a source of supply to the working end of said cylinder throughout said movement of the movable part; and automatic means, actuated as a result of operation of said movable part, for controlling the escape of exhaust fluid from the opposite end of the cylinder so as to retard said flow during movement of said movable part until it reaches a point a predetermined distance from said cooperating part and then cause free flow of the exhaust until the cooperating parts engage, whereby to regulate operation of said movable part so as to prevent slamming of said cooperating parts.

12. The combination in a die casting machine of a pair of cooperating parts adapted for movement relatively to each other to move said parts into and out of contact; power actuated means for imparting said movement to one of said parts, said means including a cylinder and a piston adapted for limited movement in said cylinder to operate said movable part; means for feeding fluid under pressure from a source of supply to the working end of said cylinder throughout said movement of the piston; and automatic means, actuated as a result of operation of said movable part for controlling the escape of exhaust fluid from the opposite end of the cylinder so as to cause free flow thereof during operation of the piston within the portion of its movement adjoining its operating limit, but retard said flow during operation of the piston beyond said portion of its movement, whereby to regulate operation of said piston and said movable part.

13. The combination in a die casting machine of a pair of cooperating parts adapted for rela-

5 tive movement towards and into contact with each other; power actuated means for imparting said movement to one of said parts, said means including a pressure fluid cylinder and a piston adapted for limited movement in one direction in said cylinder to operate said movable part; means for feeding pressure fluid from a source of supply to the working end of said cylinder throughout said movement of the piston; and 10 10 automatic means, actuated as a result of operation of said movable part, for controlling the escape of exhaust fluid from the opposite end of the cylinder so as to retard said flow during movement of the piston until it reaches a point 15 15 a predetermined distance from said limit of movement and then cause free escape of the exhaust until said limit is reached, whereby to regulate operation of said movable part so as to prevent slamming of said cooperating parts.

20 14. The combination in a die casting machine of a pair of separable, cooperating parts adapted for movement relatively to each other; power actuated means for imparting said movement to one of said parts, said means including a pressure 25 25 fluid cylinder and a piston adapted for limited reciprocatory movement in said cylinder to operate said movable part; means for feeding pressure fluid from a source of supply to the work-

ing end of said cylinder throughout the stroke of the piston in one direction; and automatic means, actuated as a result of operation of said movable part, for controlling the escape of exhaust fluid from the opposite end of the cylinder so as to cause free flow thereof at the ends 5 of the piston stroke and retard said flow during the intermediate portion of the stroke, whereby to operate said movable part so as to prevent slamming and insure sudden separation of said 10 10 cooperating parts.

15 15. The combination in a die casting machine of a multi-part die, one of said die parts being adapted for movement relatively to a predetermined limit; means adapted for application of force thereto to actuate said movable die part; controlling means for causing a relatively heavy application of force to said actuating means when the movable die part is operating relatively closely to said limit of movement and a reduced application of force thereto when said part operates farther from said limit; and means for adjusting said controlling means so as to vary the range of movement of the movable die part within which said relatively heavy application of force 20 20 takes place.
